UNITED STATES PATENT OFFICE.

MICHAEL PARIDON, OF BARBERTON, OHIO, ASSIGNOR OF ONE-HALF TO HENRY A. RUDD, OF BARBERTON, OHIO.

BEAD-PLACING DEVICE FOR USE IN BUILDING PNEUMATIC-TIRE SHOES.

1,200,014

Specification of Letters Patent.

Patented Oct. 3, 1916.

Application filed June 2, 1916. Serial No. 101,287.

To all whom it may concern:

Be it known that I, MICHAEL PARIDON, a citizen of the United States, residing at 1407 Norton avenue, Barberton, in the county of Summit and State of Ohio, have invented new and useful Improvements in Bead-Placing Devices for Use in Building Pneumatic-Tire Shoes, of which the following is a specification.

- 10 This invention relates to devices for use in the building up of a pneumatic-tire shoe and has a special relation to a device for securing the accurate placement of the bead cores during the building operation.
- 15 The object of the invention is to provide a simple device by which the cores or reinforcing portions of the beads of pneumatic-tire-shoes may be accurately and quickly positioned during the tire-shoe 20 building operation.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and 30 modifications can be resorted to which come within the scope of the matter hereinafter claimed.

In the drawings in which similar reference numerals indicate like parts in the different figures, Figure 1, is a vertical section transversely of a core used for building pneumatic-tire-shoes with a portion of a shoe thereon and also showing my device in operative relation therewith, and Fig. 2, is 40 a side elevation of a device embodying my invention.

The device which forms the subject matter of this invention comprises a split ring 1 of partially resilient material, provided with separated ends 2 having a normal tendency to expand outwardly or radially and furthermore, provided with an outer face of periphery 3 constituting a seat or gage positioning the bead cores. The outer periphery 50 3 is furthermore provided with a rabbet comprising a cylindrical face 4 and a radial face 5. Adjacent to the separated ends 2 the member is provided with operating handles 6.

55 The circumference of the cylindrical face

4 is normally such, that, in order to seat the device in position the handles 6 must be drawn toward each other to reduce the diameter of the entire device and when released the device springs outwardly sufficiently to 60 seat itself and is therefore self-retaining.

As already stated the device is adapted to be used in combination with a tire-shoe building core such, for instance as the core 10 shown in Fig. 1 which is of the usual 65 type provided with an inwardly-extending flange 11. In using the device the outer face of the core 10 is covered with one or more layers of fabric or other strength-giving material from which the tire-shoe 70 is to be constructed and while the core is suitably supported the handles 6 and 7 are drawn toward each other to reduce the diameter of the cylindrical face 4 sufficiently to permit it to be positioned within the inner 75 face of the flange 11 and when pressure is removed from the handles of the member 1, it expands of its own resilience causing the cylindrical face 4 to seat against the inner face of the flange 11 and with the radial 80 face 5 in lapping or contacting engagement with one of the side faces of the flange 11. By thus positioning the member 1 the outer face 3 will provide a seat or gage extending circumferentially of the core-body and at a 85 predetermined distance from the inner face of the flange 11 and constitutes an abutment and support for accurately positioning the beads 12 which are applied to the outer face 90 of the strength-giving member 12 and are 90 accurately located by means of the member 1. After positioning the beads 12 and causing them to adhere to the member 12 the member 1 is contracted in diameter and removed from the core after which the balance of the tire-shoe is made up in the 95 usual manner.

It will be obvious, of course, that in building up a tire-shoe it will be easier to simultaneously employ two similar members for 100 positioning the beads but it will be apparent that a single member may be used by reversing its position and putting the bead cores on one at a time.

I claim,

1. A bead positioning device for use in building pneumatic-tire-shoes comprising an outwardly-expansible split-ring provided with a face adapted to coact with the inner face of the shoe building core and 110

another portion of the face constituting a guide and bead-core positioning medium.

2. A bead-core positioning device for use in building pneumatic-tire-shoes comprising a split outwardly-expansible ring having portions adapted to coact with a shoe-building core and other portions furnishing a bead-core positioning seat.

3. A device of the type described comprising a split outwardly-expansible ring adapted to be sprung into position within a tire-shoe-building core with a portion of said ring constituting a bead-core positioning seat.

10 4. A device of the type described comprising a split annularly-fashioned outwardly-expansible member the peripheral portions of which are adapted to receive the inwardly-extending portions of a core and

furthermore provided with an outwardly-projecting bead-core positioning element.

5. A device of the type described comprising a split annularly-fashioned outwardly-expansible member the outer face of which is adapted to coact with the inwardly-extending portions of a core and further provided with an outwardly positioning bead-core positioning surface.

6. A device of the type described comprising an outwardly-expansible split annulus provided with handles adjacent to the split portions and furthermore provided with a periphery adapted to coact with the inner portions of the core and constitute a bead-core-positioning medium.

In testimony whereof I have hereunto set my hand.

MICHAEL PARIDON.
